H. Clayton,
Steam Slide Valve.

No 23,448.

Patented Apr 5, 1859.

Inventor.
Henry Clayton

UNITED STATES PATENT OFFICE.

HENRY CLAYTON, OF TAMAQUA, PENNSYLVANIA.

VALVE ARRANGEMENT OF STEAM-ENGINES.

Specification of Letters Patent No. 23,448, dated April 5, 1859.

To all whom it may concern:

Be it known that I, HENRY CLAYTON, of Tamaqua, in the county of Schuylkill and State of Pennsylvania, have invented a new and useful Improvement in Direct-Action Steam-Engines; and I do hereby declare that the following is a full, clear, and exact description of the same, reference being had to the accompanying drawings, forming part of this specification, in which—

Figure 1, is a side view of a pumping engine with my invention applied, exhibiting the steam valve and apparatus for operating the same in section. Fig. 2, is a transverse section of the same in the plane indicated by the line x, x , in Fig. 1. Fig. 3, is a section of the exhaust box of the small engine which operates the main valve. Fig. 4 is a front view of one of the adjustable sliding shutters applied to the ports of the main valve.

Similar letters of reference indicate like parts in all the figures.

My invention is applicable to direct-action engines for all purposes, such as pumping, or driving piston blowers, reciprocating saws, or any machinery or apparatus which requires a reciprocating rectilinear motion only.

One feature of my invention is more particularly intended for engines in which the resistance to the movement of the piston or force required to drive it is greater in one direction than in the other, as for instance the pumping engines employed in raising water from mines. This feature consists in the employment, in combination with a slide valve which is constructed with ports to admit the steam to the cylinder ports, of one or more adjustable shutters, that is to say, one shutter for either or each port, so applied as to permit the area of opening of one or both ports to be varied or adjusted according to the amount of steam required to act upon the piston. By this means I am enabled to overcome the many difficulties which have heretofore attended the raising of water from mines of great depth and the use of pump rods of such enormous weight as are indispensable in such cases.

Another feature of my invention relates to the driving of slide valves applied to

direct-action steam engines, by a small steam engine provided for the purpose; and this feature consists in a certain mode of applying a valve to control the exhaust of the steam from the cylinder of such smaller engine for the purpose of making it constitute a cushion within said cylinder to regulate the length of stroke of the valve-driving piston.

To enable others skilled in the art to make and use my invention, I will proceed to describe its construction and operation.

A, is the steam cylinder having its piston rod B, connected with the pump rod.

C, is one of the pumps, of which there are supposed to be two, arranged side by side.

D, is the valve chest.

F is the main valve of the engine, which is of the well-known three-port kind containing two steam ports a, a' , and an exhaust port b , working in connection with the usual arrangement of steam and exhaust ports c, c', d , in the cylinder.

E, E' , are two adjustable shutters for varying the area of opening of the ports a, a' , of the valve F, one for each port, said shutters consisting of plates or blocks of metal of a size and form to cover the said ports a, a' . These shutters are fitted to the back of the valve so as to be capable of sliding thereon that either one may be made to cover a greater or less portion of its respective port or to leave the same entirely open or closed. They are made adjustable independently of each other by separate screws G and G', arranged parallel with the valve stem e , the former of which screws is made hollow for the stem of the latter to pass completely through it. The threads of these screws G, G', fit to female screws provided in the shutters. The screw G is provided with a journal shouldered at its ends to fit into a journal box f , provided for it on the back of the valve F, and so, while permitted to turn, it is prevented moving longitudinally independently of the valve. The said screw has a hollow cylindrical stem which works through a stuffing box g , in the rear end of the valve chest D, outside of which it is furnished with a wheel or handle h , to turn the screw without opening the steam chest. The stem of the screw G', is filled with a stuffing box j , at the outer end of the stem of the

- screw G, and the gland of this stuffing box serves to act in combination with a shoulder within the last mentioned stem and a collar i, on the stem of the screw G', to prevent any longitudinal movement of the latter screw independently of the valve. The stem of G', is furnished like that of G, with a wheel or handle h', outside the valve chest to turn it.
- 10 In the operation of the engine, the shutters E, E', move along with the valve in the same manner as though they were permanently attached thereto, the stem of the screw G, working back and forth through the stuffing box g, as the valve travels, back and forth and the parts a, a', each always remaining in the same degree covered or uncovered till some variation is found necessary when either shutter may be moved in a direction to cover a greater or less portion of, or be made to entirely open or close its respective port by turning its respective screw by the handle or wheel h, or h', outside the steam chest.
- 15 As an illustration of the advantage resulting from the application to the valve of the shutters above described, I will remark that in pumping-engines for mines it has been common to use a single-acting steam cylinder, and to apply the steam to operate in a direction to raise the pump-rods and plungers or pistons, and to make the latter heavy enough to descend and force up the whole column of water in the discharge pipe, but much difficulty has been experienced in constructing the pump rods of the proper weight for this purpose. Now, by using a double-acting engine with a shutter applied to the upper valve port as described and
- 20 making the pump-rods somewhat lighter than is requisite to make them overcome the weight of the column of water, the shutter can be adjusted to give the upper port just opening enough to admit the small quantity of steam above the piston that is necessary to make up for the deficiency in the weight of the rods, &c., and thus the whole difficulty is overcome. I propose, in applying the invention to pumping engines, to use two force
- 25 pumps driven by the same rod and to make the weight of the rod or rods which work them about equal to the weight of the column of water forced from one pump, so that the steam piston in its down stroke will, when both pumps are in operation, require steam enough to drive one pump; but if one pump should get out of repair, it may be disconnected and the other one continued in operation, the steam in that case requiring to be
- 30 shut off entirely or nearly so from above the piston by the shutter E, as the pump remaining will have the whole weight of the rod to drive it down; and the same or nearly the same amount of steam will be requisite
- 35 on the lower side of the piston to raise the

rod and its appendages. It will thus be seen that the application of the adjustable shutters to the valve affords facility for regulating the admission of steam to either side of the piston as may be required according to the force required in either direction.

H, is the cylinder of the small engine by which the main valve F is operated; the piston I, of the said engine being attached to the stem e, of said valve F. This small engine is fitted with a short slide valve m, of the common kind, which is connected with the arm n, of a rockshaft p, and the arm q, of which is operated upon to produce the necessary movement of the said valve m, by tappets r, r', on a rod s, attached to and moving with the piston rod B, or said tappets may be on the piston rod itself. t, is the exhaust passage of the cylinder H, having interposed between it and its escape pipe u, a valve box J, containing a slide valve L, whose parallel faces fit to slide between the back and front of the said box. This valve has in its bottom edge a tapering arched passage v, the larger end of which is next the steam cylinder H, and the smaller end next the entrance to the escape pipe; and said valve has a stem w, connected with its upper end by a spring y, the said spring leaving the said stem free to turn, and the said stem screwing through the top of the box J. By screwing down the stem w, the smaller opening of the taper passage v, is made to close a greater or less portion of the entrance to the escape pipe u, and so more or less to check the exhaust of steam from the cylinder H, and cause the cushioning of its piston I, as it approaches either end of the cylinder, thereby preventing it striking the ends of the cylinder. The stroke of the piston I, is also to some extent varied by checking the exhaust more or less, the stroke being shortened as the exhaust is more checked and vice versa. The object of the spring y, is to prevent the blowing out of the ends of the cylinder H, by the too great compression of the steam therein, such pressure acting against the tapered interior of the arched passage v, and raising the valve, and thereby uncovering a greater portion of the entrance to the escape pipe.

I do not claim the fitting of plates or blocks to the back of a slide valve when they are intended to operate as cut-offs for using the stem expansively in the cylinder. But

What I claim as my invention and desire to secure by Letters Patent, is:

1. The employment, in combination with a slide valve, of one or more shutters applied and secured thereto, substantially as described, to vary and regulate the area of opening of the port or ports, as and for the purposes herein specified.

2. Combining the two shutters E, E', (when two are employed) with the slide

valve by means of two screws G , G' , one of whose stems passes through the other, which turns in a bearing on the back of the valve, and both of which stems pass through one end of the valve chest, the whole operating substantially as herein described.

3. The valve L , with its screwed stem w ,

or its equivalent and spring y , arranged and applied substantially as described, for the purpose herein set forth.

HENRY CLAYTON.
